FIG. 1.

FIG. 2.

Inventor
W. J. McLean.

J. C. Simpson

By Attorney &

UNITED STATES PATENT OFFICE.

WILLIAM J. MCLEAN, OF EVERETT, MASSACHUSETTS.

TOOTH-BRUSH HANDLE.

1,211,468.

Specification of Letters Patent.

Patented Jan. 9, 1917.

Application filed July 23, 1915. Serial No. 41,546.

To all whom it may concern:

Be it known that I, WILLIAM J. MCLEAN, a subject of the King of England, residing at Everett, in the county of Middlesex, State 5 of Massachusetts, have invented certain new and useful Improvements in Tooth-Brush Handles; and I do hereby declare the following to be a full, clear, and exact description of the invention, such as will enable 10 others skilled in the art to which it appertains to make and use the same.

The present invention is directed to improvements in tooth brush handles, and has for its object to so construct a handle that 15 a name printed on a card may be attached thereto easily and quickly.

A further object of the invention is to provide a tooth brush handle of transparent material, and so constructed that a card having 20 printed thereon the owner's name may be attached thereto.

With these and other objects in view, this invention resides in the novel features of construction, formation, combination and 25 arrangement of parts to be hereinafter more fully described, claimed and illustrated in the accompanying drawing, in which:—

Figure 1 is a perspective view of the device. Fig. 2 is a similar view showing the 30 brush handle in a position for receiving the card.

Referring to the drawing 1 designates the head of the tooth brush, which is provided with the usual bristles 2. The head has 35 formed integral therewith a handle 3, said head and handle being formed from transparent material.

The handle 3 is kerfed, as at 4 to provide sections 5 and 6, and since the handle is 40 made from transparent celluloid or the like, which is resilient, it is obvious that the sections 5 and 6 will spring toward each other.

The section 6 is provided adjacent its free 45 end with a pair of spaced ribs 7, which are adapted to bite into the card 8, when the same is placed between the sections 5 and

6, thereby holding the card against accidental displacement.

Since the sections 5 and 6 are transparent it is obvious that the name of the owner 50 which is printed upon both sides of the card may be clearly seen. By providing a pair of ribs 7 the card will not only be prevented from moving longitudinally, but will be prevented from swinging, or moving laterally. 55

Upon placing the card between the sections 5 and 6 it is only then necessary to grasp the free ends of the sections and force the same toward each other, whereupon the ribs 7 will bite into the card, thereby firmly 60 holding the same in place. Since the sections 5 and 6 are necessarily resilient, the same will engage the opposite sides of the card, thereby holding the card clamped therebetween.

It will be of course understood that a handle such as described may be used in connection with other toilet articles, such as hair brushes, nail brushes and the like.

What is claimed is:—

1. A tooth brush having a handle of transparent material and kerfed longitudinally to provide resilient sections, a card engaged between the sections and means for holding the card between the sections, said 75 card having designating characters thereon.

2. A tooth brush having its handle formed from transparent material, said handle being kerfed longitudinally to provide resilient sections, a card engaged between the 80 sections one of said sections having ribs disposed transversely thereof for engaging the card when placed between the sections, said card having printed thereon designating characters.

In testimony whereof, I affix my signature, in the presence of two witnesses.

WILLIAM J. MCLEAN.
